(57) CLAIM

The ornamental design for a beach tent, as shown and described.

DESCRIPTION

FIG. 1 is a front, top and left side perspective view of a beach tent, showing my new design;

FIG. 2 is a rear, bottom and right side perspective view thereof;

FIG. 3 is a rear view thereof;

FIG. 4 is a front view thereof;

FIG. 5 is a right side view thereof;

FIG. 6 is a left side view thereof;

FIG. 7 is a top plan view thereof;

FIG. 8 is a bottom plan view thereof;

FIG. 9 is a front, top and left side perspective view in open state thereof;

FIG. 10 is an enlarged view of portion 10 shown in FIG. 1 thereof; and,

FIG. 11 is an enlarged view of portion 11 shown in FIG. 2. The broken lines shown in the drawings illustrate portions of the beach tent that form no part of the claimed design.
